UNITED STATES PATENT OFFICE.

CHRISTIAN SIVERTSON, OF WEST DULUTH, MINNESOTA.

MOLD.

Application filed December 13, 1920. Serial No. 430,230.

To all whom it may concern:

Be it known that I, CHRISTIAN SIVERTSON, a citizen of the United States, residing at West Duluth, in the county of St. Louis and State 5 of Minnesota, have invented certain new and useful Improvements in Molds; and I do declare the following to be a full, clear, and exact description of the invention, such as will enable others skilled in the art to 10 which it appertains to make and use the same.

This invention relates to improvements in molds, and it has more particular reference to a device of this class which is especially 15 designed for making plastic shingles.

The principal object of the invention is to provide a mold which is an improvement on similar devices for accomplishing the same result, this mold being of extreme simplicity 20 and durability, highly effective in use, and very inexpensive to manufacture.

Another object of the invention is to provide a mold which is of such construction and shape that it will form a shingle 25 having six edges, two of which are relatively short, are inclined and disposed at the points opposite one another, the mold also including means for forming an abrupt shoulder at the connecting point of one of 30 the long and short edges. Thus, a shingle is provided which can be placed in position on a roof by inexperienced persons.

A further object of the invention is to provide a mold embodying a stationary section 35 constituting the bottom and one of the end walls, and a removable section which has pivotal connection with the bottom and constitutes the opposed end wall, both of these sections being provided with spaced 40 aligned grooves for reception of partitions, whereby a plurality of shingles may be formed at each operation and the shingles and partitions readily removed with great ease and facility.

A still further object of the invention is to provide a mold embodying the aforesaid construction together with pairs of reinforcing ribs, which extend beyond the respective sections to which they are connected 50 and provide novel disconnectible hinge means for permitting separation of the sections.

Other objects and advantages of the invention will be apparent during the course 55 of the following description.

In the accompanying drawings forming

a part of this specification and in which like numerals are employed to designate like parts throughout the same:

Figure 1 is a perspective view of a mold 60 constructed in accordance with this invention.

Figure 2 is a central vertical section through the device.

Figure 3 is a transverse section taken on 65 the line 3—3 of Fig. 2, looking in the direction of the arrows.

Figure 4 is a perspective view showing the hopper removed and sections of the mold separated to permit partitions to be removed. 70

Figure 5 is a top plan view of several shingles showing the manner in which they are placed together.

Referring to the drawings, wherein the 75 preferred embodiment of the invention is clearly illustrated, it will be seen that the numeral 1 designates the stationary section which includes the bottom 2 and one of the vertical end walls 3. It is to be noted, that 80 the portion 4 which connects the bottom with the end wall is inclined for a purpose to be hereinafter set forth. The other section, which is movable, is designated by the numeral 5 and this section is disposed opposite 85 the walls 3 and 4 and constitutes the remaining end wall. Careful examination of the wall 5 will disclose the fact that it is quickly detachable from the bottom 2 and has its upper portion inclined toward the wall 3 90 as indicated at 6. With this construction and arrangement, it will be seen that a mold is formed which is open at its top and at opposite sides, and it is so shaped that when the shingle is formed, the latter 95 will be equipped with six sides, two of which are inclined, and relatively short with respect to the remaining sides; these two short sides being disposed at the points opposite one another. It is also to be stated, as be- 100

fore intimated, that with this particular kind of a mold, each of the shingles will be provided with a shoulder formed by the vertical free edge 7 of the end wall 5. As is the case with other molds of this class, 105 it is my desire to form a plurality of shingles at each operation. To this end, I provide the sections 1 and 5 with a plurality of closed spaced interiorly disposed grooves 8 and in these grooves I place a plurality 110 of partitions 9 between which the plastic material in the liquid form is poured. In

view of the peculiar internal outline or shape of the mold, it is to be noted that the partitions are shaped to fit between the sections of the mold.

5 To facilitate the removal and insertion of the partitions and also to facilitate ready and easy removal of the shingles from the mold, I so connect the end wall 5 with the bottom 2 that this end wall may be swung 10 down to the position shown. Any means may be employed for permitting this, however, I prefer to make use of the construction shown. To this end, it will be seen that each of the sections 1 and 5 is provided with a 15 pair of spaced reinforcing ribs 10 and 11 respectively, these ribs being arranged on the exterior of the sections so as not to interfere with the formation of the shingles and at the same time to provide novel means for supporting the mold and increasing the life of the latter. Going into more detail on this construction, I may add that only the horizontal portion of the ribs 10 serve as the above referred to means for supporting the 20 mold on the ground, and in view of the fact that they retain the mold in spaced relation from the ground, it will be seen that the life of the latter will be increased. It is to be noted that the lower ends of the ribs 11 and 25 the adjacent ends of the ribs 10 are extended beyond the sections by which they are carried, the ribs 11 being provided at this point with notches 12 while the corresponding portions of the remaining ribs carry a pivot 30 pin 13 receivable in these notches. This construction and arrangement permits the section 5 to be swung to a position to facilitate the insertion and removal of the partitions and permits this section to be disconnected whenever necessary or desired. For the purpose of retaining the movable end wall 5 in operative position, I make use of 35 a pair of notched latch arms 14 which are carried by the stationary sections, the 40 notches being co-operative with pivotal studs 45 15 on the vertical edges of the other section. Of course, when the device is in use, a hopper 16 of any suitable construction will be employed to insure quick filling of the spaces 50 between the partitions with concrete or cement.

In Figure 5 I have shown several of the shingles as formed with a mold of this construction. Referring to these shingles, it 55 will be seen that each one includes six edges or sides, those designated by 17 being disposed opposite one another, inclined, and shorter than the remaining ones 18. It is also to be noted that each shingle is provided 60 with a shoulder 19 formed at the connecting point of one of the long edges and the adjacent short edges, this shoulder being disposed at right angles to said long edge. With shingles of this construction, it will be very 65 easy for inexperienced persons to arrange

them and secure them in the proper position on the roof. By providing the shingles with these shoulders, it will be seen that the proper relative positions of the various shingles may be obtained and when once the 70 shingle is fixed in position, it will very rarely slip out of place, even before it is nailed or secured to the roof.

In view of the foregoing detailed description of this improved mold taken in connection with the accompanying drawings, it is thought unnecessary to describe the manner of using the same or the manner of making use of the improved shingles, therefore, a more lengthy description is unnecessary. 80

From the foregoing description, it will be seen that I have devised an extremely simple and highly effective mold which is of such construction and arrangement that it will form entirely new and novel shingles 85 which may be placed in position by inexperienced persons. Furthermore, the removable hinged section of the mold will insure quick and easy removal and insertion of the partitions and quick removal of the shingles after 90 the latter have become hardened. The mold is very compact and light in weight and is highly efficient in every way. These and other advantages and features of the device, have, no doubt, become apparent from the 95 foregoing description.

Since probably the best results may be obtained with the construction and arrangement shown and described, this construction and arrangement is taken as the preferred 100 embodiment of the invention. However, I wish it to be understood that various minor changes in the shape, size, and arrangement of parts may be resorted to without departing from the spirit of the invention or the 105 scope of the subjoined claims.

I claim:

1. A mold comprising a stationary section having a bottom, a vertical end wall and a lower corner wall extending diagonally from the bottom to the lower end of the end wall, a movable section including a portion hingedly connected with the bottom and forming a vertical end wall for the mold, and a section extending diagonally therefrom to provide a diagonally disposed upper corner wall extending parallel to the lower corner wall and having its free end cut to extend parallel to the vertical end wall and providing a reduced neck at the upper end of the mold, 110 and means for releasably holding the movable section in an operative position. 115

2. The structure of claim 1, and partitions positioned vertically within the mold and extending between the bottom, end walls and upper and lower corner walls and conforming to the contour of the spaced enclosed thereby whereby a plurality of plastic shingles may be formed with each provided with tapered upper and lower end portions, and 120 125 130

relatively short side edges intermediate its length and an outstanding shoulder extending from the upper end of one side edge to the tapered upper end portion of the shingle.

5. 3. The structure of claim 1 having the sections of the mold provided with longitudinally extending spaced bracing strips having extended end portions, and a pivot rod carried by the extended end portions of the

10 strips of one section, the extended end por-

tions of the strips of the other section being provided with notches receiving the rod to pivotally connect the strips of the sections and hingedly mount the movable section for movement into and out of an operative position and permit removal of the movable section from the rod.

In testimony whereof I have hereunto set my hand.

CHRISTIAN SIVERTSON.
